United States Patent Office.

WILLIAM H. SMITH, OF NEW YORK, N. Y., ASSIGNOR TO HIMSELF AND
ISRAEL HECKER.

Letters Patent No. 77,774, dated May 12, 1868.

SINKER FOR FISHING-LINES.

The Schedule referred to in these Letters Patent and making part of the same.

TO ALL WHOM IT MAY CONCERN:

Be it known that I, WILLIAM H. SMITH, of New York, in the county of New York, and in the State of New York, have invented certain new and useful Improvements in Sinkers for Angling-Lines; and do hereby declare that the following is a full, clear, and exact description thereof, reference being had to the accompanying drawings, and to the letters of reference marked thereon.

In the annexed drawings, making part of this specification, A A are two conical-shaped metallic tips or ends to a sinker, which are made hollow from end to end. In Figure 2, the outer ends of these tips are provided with metallic pins, B B, and these pins have swivel-rings, C C, secured to their outer ends.

To the inner end of one of these tips is secured a screw-shaft, G, and in the inner end of the other is a nut, H, to fit the thread of the shaft.

D D represent a series of metallic disks, which are provided with holes through their centres. These disks slip over the shaft G. The shaft is made long enough to receive several of the disks, so that the sinker may be made heavier, if desired. The screw-shaft in Figure 1 is hollow, so that the line can be passed through the sinker in the line x x.

In fig. 2, the line is passed through the swivel-rings C C, and runs on the outside of, instead of through, the centre of the sinker. When the line passes through the sinker, as in fig. 1, it can be fastened or secured to it by means of pins, or by some adjustable mode by which the sinker may be shifted on the line at pleasure.

The sinker is made lighter by decreasing the number of disks, and heavier by increasing them, of course.

The nut H may be dispensed with, by making a female screw in the opposite inner end of the tip to that which contains the shaft G.

Having thus fully described my invention, what I claim as new, and desire to secure by Letters Patent, is—
Making a sinker in two parts, and in such a manner that sections or disks may be added to or taken from it, for the purpose of increasing or diminishing its weight, substantially as herein set forth.

In testimony that I claim the foregoing, I have hereunto set my hand and seal, this 4th day of November, 1867.

WM. H. SMITH. [L. S.]
